Filed May 19, 1960, Ser. No. 60,654

Term of patent 14 years

(Cl. D33—19)

FIG. 1 is a front elevational view of a locker door or the like showing our new design;

FIG. 2 is a transverse sectional view thereof, taken at about the line 2—2 of FIG. 1;

FIG. 3 is a side elevational view thereof, taken from the right of FIG. 1;

FIG. 4 is a vertical sectional view thereof, taken at about the line 4—4 of FIG. 1;

FIG. 5 is a front elevational view of a modified form of the locker door;

FIG. 6 is a transverse sectional view thereof, taken at about the line 6—6 of FIG. 5;

FIG. 7 is a side elevational view thereof, taken from the right of FIG. 5; and

FIG. 8 is a vertical sectional view thereof, taken at about the line 8—8 of FIG. 5.

The dominant features of our design are shown in full lines on the drawings.

We claim:

The ornamental design for a locker door or the like, substantially as shown and described.
